UNITED STATES PATENT OFFICE

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,134,732.

Specification of Letters Patent.

Patented Apr. 6, 1915.

Application filed September 23, 1913. Serial No. 791,311.

To all whom it may concern:

Be it known that I, FREDERIC P. GATES, a citizen of the United States of America, and residing at Hartford, in the county of 5 Hartford and State of Connecticut, have invented a certain new and useful Improvement in Electric Switches, of which the following is a specification.

My invention relates to electric switches 10 and particularly to switches for use in electric lamp sockets, the object of my invention being to provide an improved switch mechanism adapted to operate upon a rotation of the switch key in either direction and affording a double quick make and quick break at the contacts, while the mechanism as a whole is economical to manufacture, strong and efficient in operation.

In the accompanying drawing, Figure 1 20 is a vertical section of a lamp socket in which my improved switch is embodied in one form; Fig. 2 is a plan of the lower insulating button showing the switch mechanism in position; Fig. 3 is a side elevation 25 of the switch mechanism partly in section; Fig. 4 is a vertical section on the line 4—4, Fig. 3. Fig. 5 is a view similar to Fig. 4 with the switch piece in another position.

The socket here shown comprises the 30 usual shell 5 and cap 6 with insulating lining 7 within which are arranged the porcelain buttons A and B united in well understood manner by screw bolts 8 and 9 passing therethrough. These buttons are recessed on their meeting faces to form a switch chamber 10 in which the switch mechanism hereafter described is arranged.

Current is led to the socket through the 40 wire terminals 11 and 12 mounted on the button B. Terminal 11 is in constant electrical connection with the socket center contact 13 by means of the rivet 14 which passes through and secures their respective bases to the button B. The other terminal 45 12 clamps in position the spring switch terminal 15 which extends therefrom to one side of the switch chamber. The second spring switch terminal 16 is provided with a shank lying in the groove 17 in the side 50 of the button B and angled beneath the base of the shell contact 18 of the socket to which it is electrically connected by the bolt 9.

The switch piece 19 comprises a bar of 55 angled metal, the ends of which engage be-

tween and spread the switch terminals, 15 and 16 in "on" position of the switch. It is loosely mounted on the spindle 20 which is journaled in the uprights 21—22 of the switch frame and rotated in either direction 60 by the thumb key 23. A screw 24 threaded into the base of the switch frame holds the latter rigid on the button A. Fast on the spindle 20 is a yoke 25 and the ends 26 of the coil spring 27 engage opposite sides of the yoke and also of the switch piece 19. Lugs 28 may be angled from the body of the latter to serve as abutments for the spring ends. Detent shoulders 29, 30 are formed on opposite sides of the axis of the 70 switch piece to coöperate with the detent bars 31, 32 sliding in the uprights of the frame and serving to temporarily restrain the switch piece during the partial rotation of the yoke 25 by the switch key 23 whereby the spring 27 is put under tension. A cam rib 33 rotating with the switch spindle engages notches in the detent bars and moves the latter into and out of stop position. In position of rest both detents 31 75 and 32 project through the upright 22 into the path of the detent shoulders 29 and 30 on the switch piece. These shoulders are of such extent and the detents are so arranged, that the latter lie in substantial engagement 80 either with both sides of one shoulder or between circumferentially adjacent sides of the opposite shoulders. Consequently in whichever direction the switch spindle is rotated, the switch bar is temporarily restrained by one or the other of the detent bars. As the spindle rotates, the cam rib 85 33 moves one or the other of the detent bars out of the path of the switch piece, depending upon the direction of rotation. The 90 movement of the yoke 25 being slightly in excess of the arcuate movement of the switch piece, on a change of position of the latter, the spindle is rotated slightly in a reverse direction on the release of the key 100 23, and the effect of this "return" movement is to throw the freeing detent out again, so that the detents take up the position of rest, above mentioned, in which they engage the switch piece to prevent rotation 105 in either direction.

The action of the switch is quick, its break is wide, and its operation certain since the retents are in constant engagement with the rib 33 and their position thus posi- 110

tively controlled. The mechanism may be assembled on its frame before being mounted on the button A, and this simplifies the assembly of parts in the manufacture of the device, while the switch parts as a whole are few and simple to make.

Various modifications of the construction will readily suggest themselves and the details shown are to be regarded as merely an exemplary embodiment of my invention.

I claim as my invention:

1. In an electric switch, the combination of a rotatable spindle, a switch piece freely journaled thereon, a pair of detents normally engaging the same to temporarily restrain said switch piece upon the rotation of said spindle, cam means moving with the spindle and engaging said detents to move the latter longitudinally of the spindle, said cam means being of a contour such that it moves one of said detents out of engagement with the switch piece after partial rotation of the spindle, while maintaining the other in engaging position at the moment of the escape of the switch piece, a switch spring and means for placing the spring under tension on the rotation of the switch spindle.
2. In an electric switch, the combination of a switch frame, a switch spindle journaled therein, a switch piece freely journaled on said spindle, a switch operating spring, detents slidably mounted in said frame and moving in the direction of the length of said spindle, and a cam rotating with said spindle and engaging said detents to move the latter into and out of engagement with said switch piece.
3. In an electric switch, the combination of a switch frame, a spindle journaled there-in and rotatably in either direction, a switch piece freely journaled on said spindle, a

switch operating spring detents slidably mounted in said frame and movable longitudinally of said spindle, and cam means moving with said spindle and engaging said detents to move one of the latter out of operative engagement with the switch piece while maintaining the other in position to halt the switch piece upon the partial rotation of the spindle in either direction.

4. In an electric switch, the combination of a switch spindle and a switch piece mounted thereon having arcuate detent engaging shoulders, a switch operating spring, a pair of detents movable longitudinally of the spindle and spaced apart to embrace one of said arcuate shoulders in one position of the switch and to engage circumferentially adjacent faces of said shoulders in the other position of the switch, together with cam means on the spindle for moving one of said detents out of engaging position while maintaining the other in stop position on the partial rotation of the spindle in either direction.

5. In an electric switch, the combination of a switch spindle rotatable in either direction and a switch piece mounted thereon having a pair of stops on opposite sides of its axis, and a pair of detents, means for operating the same to successively engage first on opposite sides of one stop and then between circumferentially adjacent faces of both stops on successive positions of the switch piece.

In testimony whereof I have signed my name to this specification, in the presence of two subscribing witnesses.

FREDERIC P. GATES.
